UNITED STATES PATENT OFFICE.

JOHN J. MORAN, OF CLEVELAND, OHIO.

BUILDING-BLOCKS.

1,290,287.

Specification of Letters Patent

Patented Jan. 7, 1913.

Application filed February 5, 1912. Serial No. 143,430.

To all whom it may concern:

Be it known that I, JOHN J. MORAN, a citizen of the United States, residing at Cleveland, in the county of Cuyahoga and

5 State of Ohio, have invented certain new and useful Improvements in Building-Blocks, of which the following is a specification, reference being had to the accompanying drawings.

10 This invention relates to certain new and useful improvements in building blocks or wall units, and has for its primary object to provide a building block which is constructed to provide a plurality of air passages and 15 load bearing webs which will be in perfect alinement when arranged either horizontally or vertically in the construction of a building wall.

It is another object of my invention to 20 provide a wall unit of the above character which is of such construction that the several units may be readily bonded or jointed together in the erection of the wall, and considerable time and labor saved.

25 It is a further general object of my invention to provide a wall unit of the above type which can be manufactured in the form of tile, or of any desired cementitious material and at relatively small cost.

30 With the above and other objects in view, my invention consists in the novel features of construction, combination, and arrangement of parts to be hereinafter more fully described, claimed and illustrated in the accompanying drawing, in which,

Figure 1 is a perspective view of a wall unit or building block as the same is arranged in providing vertical air spaces or passages in the wall;

40 Fig. 2 is a horizontal sectional view of the block;

Fig. 3 is a perspective view showing the block arranged to provide horizontally extending air passages in the building wall;

45 Fig. 4 is a vertical sectional view of the block disposed in the latter position; and

Fig. 5 is a face view of a building wall constructed with my improved blocks or units.

50 Referring in detail to the drawing, 5 designates the building block or unit as a whole, which may be formed from tiling material, or cast or molded from concrete or cement. This block may be of any desired dimensions, but for ordinary wall construction is preferably of general rectangular

form. In Fig. 1, the air spaces 6 of rectangular form extend in spaced relation to each other through the body of the block or unit and are separated by means of the relatively 60 thick webs 7, said webs being preferably of uniform thickness. The block is shown in the position in Fig. 1 which it will occupy when embodied in the wall structure, so that the passages 6 will extend vertically and 65 communicate with each other through the several superposed blocks or units. Each side face of the block is provided with spaced, rectangular channels 8 in line with the passages 6 and of corresponding width. Each 70 of these channels 8 constitutes one-half of a complete air passage, the other half of which is produced by the adjacent wall block or unit. The central passage 6 in the block is of greater area than the remaining passages 75 in the block and the central channels 8 of correspondingly greater depth than the end channels. Thick webs 9 separate the end air passages 6 from the end channels 8 while relatively thin webs 10 separate the central 80 passage 6 from the central channels 8. The formation of the channels 8 in the side faces of the block produces one-half of the separating webs 7, and each of these web sections is provided in its outer face with a rec- 85 tangular, longitudinal groove 11 for the purpose of receiving mortar or other bonding material, whereby the adjacent blocks or units in the building wall are united or securely bonded together. One or both of the 90 end faces 12 of the block may be finished in any desired manner, one of said finished end faces of the block constituting a part of the outer face of the wall.

The blocks or units are arranged in super- 95 posed relation, with the webs 7, 9 and 10 in direct vertical alinement, the air passages 6 of course being also in precise alinement with each other throughout the several blocks in the wall structure. The drawings 100 illustrate the block in the form of a single unit, but it may also be manufactured as a double unit, or of twice the face length of the block shown in the drawing. The wall may be constructed in any desired arrange- 105 ment of the single and double block units so as to produce an ornamental effect or appearance in the completed wall. The bonding material is arranged between the tiers or layers of blocks or units in the usual manner, 110 and such material also disposed in the grooves 11 in the sides of the block.

In Figs. 3 and 4 of the drawing, I have shown the block arranged in position so that the passages 6 will extend horizontally of the wall. In this arrangement of the blocks, 5 the bonding material may be placed within the end channels 8 in the upper and lower faces of the block, and the grooves 11 can be eliminated. These grooves may be dispensed with in either arrangement of the 10 blocks and the bonding material simply placed upon the end faces of the web sections 7'. When the blocks are thus arranged to provide the horizontal air passages 6, 21 of the thick webs 7 of the several 15 blocks are in direct vertical alignment throughout the wall structure, thus giving an extensive load bearing area.

From the foregoing description of my improved building block or unit, it will be seen 20 that a block thus constructed is very light in weight and comparatively little material is employed in the manufacture of the block. Thus, the wall can be constructed at minimum cost and economy may also be realized 25 in the construction of the foundation for the wall in view of the fact that the weight to be supported by the foundations is greatly reduced. It is apparent, of course, that the 30 number of air passages and the connecting webs will vary in accordance with the size or form of the block or unit. The block can be constructed of all materials which are now commonly employed in the construction of building walls.

35 From the foregoing description, taken in connection with the accompanying drawing, the construction, manner of use and several advantages of my improved non-conductive wall unit will be clearly and fully understood. The device is exceedingly simple and 40 may, therefore, be manufactured at rela-

tively small cost. My improved block constructed in the manner above described also enables the wall to be constructed with expedition and with a minimum of manual 45 labor.

While I have shown and described the preferred construction and arrangement of the several parts of the invention, it is to be understood that the same are susceptible of 50 considerable modification and I, therefore, reserve the privilege of adopting all such legitimate changes as may be fairly embodied within the spirit and scope of the invention as claimed. 55

Having thus fully described my invention, what I desire to claim and secure by Letters Patent is:

A non-conductive wall unit consisting of a molded body having air passages extending through the opposite ends thereof and of the same area and a central air passage of relatively greater depth, the opposite side faces of the block being also provided with end channels of the same depth opposed to 60 the end passages in the block and a central channel of relatively great depth opposed to the central passage in the block, said passages being spaced from each other by webs of uniform thickness, the end passages being spaced from the end channels in the 65 faces of the block by webs of the same thickness and the central passage spaced from the central channels by webs of appreciably less thickness than the other webs. 70 75

In testimony whereof I hereunto affix my signature on the presence of two witnesses.

JOHN J. MORAN.
